ELECTRIC CIRCUIT BREAKER

William D. Boller, Milford, Ohio, Warren D. Berkley, Fort Wayne, Ind., Walter Ernst, Dayton, Ohio, and Edwin W. Landmeier, Covington, Ky., assignors to The Wadsworth Electric Mfg. Co., Covington, Ky., a corporation of Kentucky

Original application June 10, 1948, Serial No. 32,204, now Patent No. 2,618,716, dated November 18, 1952. Divided and this application February 16, 1952, Serial No. 274,245

4 Claims. (Cl. 200—116)

1

This invention relates to circuit breakers, and is concerned primarily with a combination switch and circuit breaker intended to control the circuits in homes and comparable places.

This application is a division of our United States Patent Application Serial No. 32,204, which was filed June 10, 1948, for "Electric Circuit Breaker," and which is now issued as United States Patent No. 2,618,716.

At the present time, the electrical installations for homes, business establishments, and other places making use of the current supply that is made available by the electric companies includes one or more circuits, each of which embraces a fuse and sometimes a switch associated therewith. When the circuit is overloaded or a short circuit develops, the fuse burns out in a well-known manner and must be replaced before service can be restored.

The present invention has in view as its foremost objective the provision of a combination switch and circuit breaker which is intended to replace the fuse and switch heretofore employed in controlling such circuits.

Under practical conditions, a plurality of circuits are ordinarily included in electrical installations of the type with which this invention is concerned and a further object of the invention is the provision of a combination circuit breaker and switch which is susceptible of being assembled in multiple or gangs with each unit controlling one circuit.

In the known combination units of the type intended to be improved by this invention, it has been the practice to provide a pair of contacts for controlling the circuit. When these contacts are in engagement, the circuit is closed and when they are spaced apart, the circuit is open. Usually one of these contacts is fixed and the other is movable. The present invention has in view as an important object the provision of a combination switch and circuit breaker of the type indicated in which both of the contacts are movable. This arrangement presents certain definite advantages. It is possible to provide for the movement of one contact into opened or closed position under the influence of a manually operable lever while the other contact is placed under the control of the circuit conditions so as to be moved into opened position under overload or short circuiting conditions. This latter contact may be moved back into circuit closing position under the influence of the manually operable lever.

To the end of keeping the contacting surfaces clean a further object of the invention is the pro-

2

vision of a combination switch and circuit breaker of the type indicated in which the contacts are separated with a wiping action in contrast to a direct pull apart.

5 In circuit breakers of the type with which this invention is concerned, the opening of the contacts is placed under the control of a bimetallic thermostat together with a so-called "rupture" magnet that is affected by the current conditions 10 to vary the strength thereof. The bimetallic thermostat is heated by overload conditions and when a predetermined condition is reached opens the contacts, whereas the rupture magnet is affected by a short circuit or other comparable 15 instantaneous condition to immediately open the contacts. It has been the practice to mount the rupture magnet on the thermostat so that it is movable therewith. However, the present invention contemplates mounting of the rupture magnet in a fixed position in the casing and an armature which cooperates therewith is carried by a latch which controls relative movement of the contacts. This arrangement presents certain advantages not only as to ease of assembly 20 but also in sureness of operation. With this arrangement, the rupture magnet is mounted with no physical connection between it and the bimetallic thermostat.

Still another object of the invention is the provision, in a combination switch and circuit breaker of the type aforesaid, of a novel assembly of a latch, keeper piece, and rivets which is highly simplified as compared to anything heretofore provided for this purpose.

35 Various other more detailed objects and advantages of the invention such as arise in carrying out the above noted ideas in a practical embodiment will in part become apparent and in part be hereinafter stated as the description of the invention proceeds.

40 For a full and more complete understanding of the invention reference may be had to the following description and accompanying drawings wherein:

45 Figure 1 is a longitudinal vertical section, taken on the line 1—1 of Figure 3, through a third modification and depicts the position of the contacts as normally closed but brings out in dotted lines the position of the contacts and associated parts when the switch is manually opened;

50 Figure 2 is a fragmentary section of the combination switch and circuit breaker of Figure 1, taken on the line 2—2 of Figure 3, with the parts in rupture position caused by circuit conditions;

55

Figure 3 is a compound vertical cross section through the unit of Figures 1 and 2, being taken about on the planes represented by the lines 3—3 of Figure 1;

Figure 4 is an enlarged detailed view in perspective bringing out the anchorage for the bimetallic thermostat of the unit shown in Figures 1, 2, and 3.

The switch and circuit breaker unit shown in the drawings is housed in the usual casing and cover assembly in which are mounted the terminal plates 164 and 165. The top wall of the casing represented at 166 is formed with an opening 167 in which is pivotally mounted an operating lever 168 which is of insulating material.

Referring to Figure 3 it will be noted that a central plate 169 is imbedded in the lever 168 and on each side of the plate 169 are outer plates 170 and 171. These outer plates 170 and 171 are joined by a flange 172 which is effective during the reset operation as will be later described.

A contact carrier 173 is pivotally connected as represented at 174 to the central plate 169. Outstanding from each side of the carrier 173 are a pair of ears 175 and 176 to each of which is anchored one end of the tension coil springs 177 and 178, respectively. The upper ends of the springs 177 and 178 are anchored to the casing and cover structure as represented at 179 and 180. The tendency of the springs 177 and 178 is to bias the contact carrier 173 in one direction or the other depending on which side of the center 174 they are located.

The lower end of the carrier 173 is provided with a contact 181 which is located within the effective zone of a permanent magnet 182 which is included for arc suppressing purposes as above pointed out. The casing structure is provided with a pair of stop members 183 and 184 which limit the movement of the carrier 173. A flexible connector 185 connects the terminal plate 164 to the contact carrier 173.

A rocker 186 is pivotally mounted as indicated at 187 to the casing structure and at its upper end has an arm 188 which is adapted to be engaged by the flange 172 for the reset operation. The lower end of the rocker 186 carries a contact 189 which is complementary to and engages the contact 181. A tension coil spring 190 has its upper end secured to the casing structure as shown at 191 and its lower end secured to the rocker as indicated at 192. This spring exerts a tendency normally urging the rocker 186 in a counterclockwise direction. The rocker 186 is provided with a stop in the form of a flange 193 which is normally engaged by a detent 194 carried at the end of a spring latch 195.

The bimetallic thermostat 196 has one end anchored to the casing structure by the anchoring member which is shown in detail in Figure 4 and which is designated 197. It will be seen that the ends of the thermostat 196 may be inserted between the fingers 198 which are alternately struck from a sheet of metal from which the member 197 is formed. After the insertion the fingers may be compressed over the end of the thermostat to effect a firm anchorage.

The outer free end of the thermostat 196 engages the detent 194 as illustrated and when the thermostat has been affected as by a predetermined overload condition it will urge the detent 194 downwardly out of the path of the stop 193. A flexible connector 199 connects the rocker 186 to the thermostat 196. A magnet is shown at 200 as mounted in the casing structure and this

magnet is provided with an armature 201 the free end of which engages the detent 194. A coil 202 is wound about the magnet 200 and one end of this coil is connected by a connector 203 with the thermostat 196. The other end of the coil 202 is connected by a connector 204 with the terminal plate 165. A stop for limiting movement of the rocker 186 in a counterclockwise direction is shown at 205 and is carried by the casing structure.

Operation of the device

Figure 1 depicts in full line the circuit closed passage in which the contacts 181 and 189 are in engagement. In this position current flows from the terminal plate 165 through connector 204, coil 202, and connector 203 to one end of the thermostat 196, then passes through the thermostat to the other end, and from there through connector 199 to the rocker 186, from the rocker 186 it passes through contacts 181 and 189 to the carrier 173, and from the latter through the connector 185 to the terminal plate 164.

When the circuit is to be manually opened the lever 168 is swung into the dotted line position illustrated in Figure 1. During this movement the springs 177 and 178 pass to the opposite side of the center 174 and therefore bias the carrier 173 so as to move the contact 181 away from the contact 189. This opens the circuit. To close the circuit all that is necessary is to swing the lever back to the full line position illustrated, which again causes the springs 177 and 178 to pass dead center and bias the carrier 173 to urge the contacts into engagement.

When a predetermined circuit condition, which may be either a short circuit which affects the magnet 200 to draw the armature 201 toward it, or an overload which affects the thermostat 196, the detent 194 is moved out of the path of the stop 193. The spring 190 is now rendered effective to move the rocker in a counterclockwise direction and thus draw the contact 189 away from the contact 181. This movement is limited by the stop 205 and when the carrier engages this stop the arms 188 will be substantially in engagement with the reset flange 172. When the circuit condition has been removed the switch is reset by first swinging the lever 168 over into the dotted line position of Figure 1. This movement is transmitted through the flange 172 and arm 188 to the rocker 186 to move the latter in a clockwise direction and again bring the stop 193 against the detent 194. After this reset operation has been carried out the circuit is closed by again swinging the lever 168 into the full line position which will bring the contact 181 into engagement with the contact 189.

What is claimed is:

1. A circuit breaker comprising, a casing, a manually operable lever pivotally mounted in said casing; a plate rigidly embedded in said lever and projecting from the end thereof within said casing, a contact carrier pivotally mounted on said plate, a pivotally mounted rocker, cooperable contacts respectively carried by said rocker and said contact carrier, a tension spring extending from said contact carrier to said casing, the pivot point at which the contact carrier is connected to said plate being shiftable in response to movements of said manually operable lever to respective over-center positions in relation to said spring for actuation of the contact carried by said carrier toward and from the contact carried by said rocker, the said rocker being biased for independent movement.

ent disengagement with the contact carrier, latch means releasable in response to overload conditions for restraining the rocker against contact disengagement movement, the said rocker having a resetting ear, plate members embedded in said operating lever at opposite sides of the plate member thereof to which the contact carrier is pivotally mounted, and a bar member extending across the latter said plate members in position to engage the resetting ear of said rocker upon actuation of said manually operable lever following release of said rocker by said latch means.

2. A circuit breaker comprising, a casing, a manually operable lever pivotally mounted in said casing, a plate rigidly embedded in said lever and projecting from the inner end thereof, a contact carrier pivotally mounted on said plate, a pivotally mounted rocker, cooperable contacts respectively carried by said rocker and said contact carrier, tension springs extending in parallelism from said contact carrier to said casing at opposite sides of said contact carrier, the pivot point at which the contact carrier is connected to said plate being shiftable in response to movements of said manually operable lever to respective over-center positions in relation to said springs, for actuation of the contact carrier toward and from the contact carried by said rocker, the said rocker being biased for independent disengagement of the contact carrier, latch means releasable in response to overload conditions for restraining the rocker against contact disengagement movement, the said rocker having a resetting ear, plate members embedded in said operating lever at opposite sides of the plate member thereof to which the contact carrier is pivotally mounted, and a bar member extending from one side plate member to the other in straddling relation to the center plate for engaging the resetting ear of said rocker upon actuation of said manually operable lever following release of said rocker by said latch means.

3. A circuit breaker comprising, a casing, a manually operable lever pivotally mounted in said casing, said lever having a plate rigidly embedded therein and having a portion projecting from an end thereof within said casing, a contact carrier pivotally mounted to the projecting portion of said plate, a rocker movably mounted in said casing, said rocker and contact carrier having co-50 operable contacts, spring means residing in oper-

ative engagement with said contact carrier for biasing it toward and from the contact of said rocker by overcenter forces in response to pivotal movement of said lever, means for operating said rocker including a latch normally holding said rocker against movement but being releasable in response to circuit overload conditions, and means for resetting the rocker after release thereof by said latch, including a resetting ear extending from said rocker, and plate members having portions thereof embedded rigidly in said lever at opposite sides of the said first plate member, said latter plate members having projected portions, and a flange portion in cross connection with the said extended portions, in position for engaging the resetting ear of said rocker arm upon actuation of said manually operable lever.

4. An electric circuit breaker comprising, a rocker member biased for automatic movement, 20 releasable means responsive to circuit overload conditions normally preventing such movement, a contact carrier having a contact engageable with said rocker member, said contact carrier being movable independently of said rocker member, 25 and means for independently moving said contact carrier and for selectively resetting said rocker member, including a pivotally mounted manual lever of insulating material having a plate partially embedded therein, a pivotal interconnection between the portion of said plate which is not embedded in said lever and said contact carrier, and a U-shaped assembly comprising plate portions which are embedded in said lever at opposite sides of said first named plate and an 30 interconnecting portion extending across the first named plate, the said rocker having a portion thereof which is engageable by the said interconnecting portion for resetting the said rocker arm by movement of said pivotally mounted lever.
